UNITED STATES PATENT OFFICE.

COURTLAND SKINNER, OF CHICAGO, ILLINOIS, ASSIGNOR TO FREDERICK C. AUSTIN, OF SAME PLACE.

ORE-CRUSHER.

SPECIFICATION forming part of Letters Patent No. 617,781, dated January 17, 1899.

Application filed January 11, 1897. Serial No. 618,765. (No model.)

To all whom it may concern:

Be it known that I, COURTLAND SKINNER, a citizen of the United States, residing at Chicago, in the county of Cook and State of Illinois, have invented a certain new and useful Improvement in Ore-Crushers, of which the following is a specification.

My invention relates to crushing-machines of the class in which the crushing or reducing action is obtained by means of balls or spheres working in annular grooves or guideways.

The object of my invention is the production of a crushing-machine having an exceedingly simple and efficient construction.

The crusher more particularly described hereinafter comprises a bed having a conical upper face which is provided with concentric annular grooves, a rotary head which is arranged over the bed and has a central feed-passage and a correspondingly concaved and grooved face, and a number of sets of balls confined in the guideways formed by said grooves. The rotary head is arranged so as to be adjustable toward and away from the bed and has its grooves, except the upper one, formed in bearings which are adjustable in turn toward and away from the bed and which are provided with elastic connections tending to normally force them toward the latter. By such arrangement material is crushed by the balls working in the guideways formed in the faces of the bed and rotary head and finds its way downward and outward in the inclined passage formed by such faces to the successive sets of balls and finally emerges at the base of such passage and is collected. In case unduly large particles of material are fed into the machine such particles when acted upon by the first set of balls may cause the rotary head to rise; but the bearing portions in which the lower grooves of the rotary head are formed, being subject to elastic connections tending to force them toward the bed, will not rise when the rotary head is lifted, but will continue to rest upon their respective sets of balls.

As a matter of further improvement the opposing faces of the rotary head and bed are

magnetic—that is to say, they are arranged so as to form surfaces of the pole-pieces of magnets. While these magnetic faces could be provided by permanent magnets, I desirably provide them by electromagnets which are energized by means of magnetizing-helices connected with a suitable source of electrical energy. By such arrangement the attraction of the magnetic faces provides a powerful, uniform, and easily-regulated crushing force in a simple, convenient, and efficient manner.

In the accompanying drawings, Figure 1 is a central vertical section of a crusher embodying my invention. Fig. 2 is a similar section of a modification of the same. Fig. 3 is a view, partly in elevation and partly in section, of a modified form of the construction illustrated in Figs. 1 and 2. Fig. 4 is a top plan of a portion of the crusher. Fig. 5 is a horizontal section taken on line 5 5 in Fig. 2, and Fig. 6 is a top plan of the crusher bed with the rotary head removed.

The crushing device illustrated in said drawings comprises several sets of metal or other suitably hard crushing-balls arranged in concentric annular series, as at A A' A'', and confined between two oppositely-arranged and relatively-rotatable surfaces. These surfaces are in engagement with the balls and are held apart, so as to provide space for the passage of the material from one set of balls to the next succeeding set. One of said surfaces is provided by a conic bed B, which is preferably stationary, and the opposing surface, which is concaved substantially with the conic-bed surfaces, is desirably provided by a rotary head C, arranged over the bed. The opposing faces or surfaces of the bed and rotary head are provided with correspondingly arranged concentric annular grooves which form annular tracks or guideways for the balls. By such arrangement the rotary head can be supported by the balls, which latter, while operating to crush the material, will also serve as antifriction-bearings for the rotary head and also maintain the said head in proper position relatively to the head over which it is to rotate. The rotary head is conveniently

operated by a rotary shaft D, which extends through a centrally-arranged bore b in the head. This shaft is suitably connected with the head and operated by any suitably-applied driving means. For example, it can be geared up with a rotary shaft E, carrying fast and loose pulleys. The rotary head is provided with a centrally-arranged feed opening or passage c, which is conveniently formed by a neck c', which rises from the head, and with the illustrated arrangement of operating-shaft the latter can be extended within the feed-opening c and connected with the head by a spider c², which while serving as a suitable connection will not close up the said opening. The space between the head and bed forms an inclined annular passage, which slopes downwardly and outwardly from the feed-opening c and which is interrupted at intervals by the sets of crushing-balls. Material fed into the feed-opening c will therefore find its way into the space or passage between the head and bed, and during the rotation of the head such material will gradually work down the incline. The sets of balls will successively act upon and pulverize the material thus passing through the machine and also permit the material to thus work downwardly toward the marginal portion of the bed, it being understood that the grooves in the opposing faces of the head and bed are relatively shallow, so as to permit suitable portions of the spaces between the balls in each set to be exposed within the space or passage between the head and bed and thereby allow the material to work between the balls. The number of balls in the set A, which is nearest the feed-opening, is small in comparison with the number in the next succeeding set A', and so on, the sets thus progressively considered being successively made up of greater numbers of balls. By this arrangement the resistance to the operation of the machine will be materially modified, it being seen that the material in its coarsest condition is first acted upon by a comparatively few balls and that as the resistance will be proportionate to the number of balls employed the limited number of balls in the first set will avoid any undesirable resistance to the rotation of the head and at the same time reduce the material, which after such reduction passes on to the next set of balls in a condition to admit of its comparatively easy further reduction by a larger number of crushing-balls.

The arrangement referred to also permits the balls to be graded—that is to say, the balls of one set can be made of a size different from the balls of the next set. Thus, for example, the balls of the first set A can be made larger than the balls of the next succeeding set A', and so on. The bed is provided with an annular marginal ledge b', on which the pulverized material deposits, and the rotary head is provided with a scraper F, which traverses the ledge and carries the pulverized material around to a discharge-

spout G. The head C is also preferably arranged so as to be capable of a limited extent of vertical play or movement, so that it will yield in case unduly coarse material should wedge in the portion of the space or passage between the feed-opening and the first set of balls. This can be provided for in any suitable mechanical way—as, for example, the upper end of the shaft D can be squared and the spider can have a correspondingly-shaped hub c³, fitted to slide upon such squared end d of the shaft.

In Fig. 2 the head is provided with annular bearings H H' H², in which the guide-grooves for the upper portions of the balls are formed. The bearing H is desirably rigid with the head, while, on the other hand, the bearings H' H² are made separate from the head and connected therewith by movable connections which permit them to constantly rest upon the balls, although the head may rise as the result of coarse material wedging in the space between the first set of balls and the feed-opening, and which also permit each bearing to rise independently should any material wedge in the space between it and the set of balls working below it. As a simple arrangement the bearings H' H² are connected with the head by stems h, which are rigid with said bearings and arranged to pass through guide-openings in the head, and in order to effectively hold these bearings down upon the balls springs h', normally under tension, are arranged between the head and the bearings. In this figure the bed is provided with a series of annular seats, in which amalgamated plates I can be placed, so as to adapt the machine to operate as a separator, it being understood that these plates are placed one upon another from time to time as needed. With such arrangement the head may be provided with pendent agitating and spreading devices K, arranged for agitating and spreading the material over the amalgamated plates, and to permit the plates to be conveniently passed through the head the latter is provided with suitable openings normally covered by removable or hinged plates L. With this construction the material can be fed into the feed-opening c, as hereinbefore set forth, and water can be discharged into such opening from a pipe M. In both of the constructions shown material can be let into the feed-opening from a hopper N, supported in any convenient way.

In Fig. 3 the adjustable annular bearings H' H² are shown respectively constructed of a series of arc-shaped sections h², and each arc-shaped section h² is provided with a couple of stems h and springs h' and also with a lug h³ or the like, which is arranged to work in a guideway formed by a couple of lugs c³, projecting downwardly from the lower surface of the rotary head C. By such arrangement the wedging of material under a portion of any bearing will not cause the entire bearing to be lifted and so interfere with the operation

of the balls in the other portions of the same, but will lift only that section thereof where the wedging occurs.

As a matter of further improvement the bed is adapted to form an electromagnet, and to such end is provided with a magnetizing-helix below its upper conical face.

As a convenient construction for the accommodation of such coil the lower end of the bed B is made considerably less in diameter than the upper portion, thus forming a core or spindle B'. The requisite number of coils of wire p to form the helix P is then wrapped about such core B', and a disk P' is fitted over the end of the latter to hold the wire in place. The rotary head is also provided with a magnetizing-helix R, which is composed of coils of wire r, wrapped about the tubular upper end c', which provides the feed-opening c. This magnetizing-helix is desirably inclosed within a metal shell or casing r'.

Conducting-wires could be attached to the helices P and R in any suitable manner, but as a preferred arrangement the bed B, rotary head C, and balls A serve to conduct the energizing-current from one helix to the other. Thus one end of the wire is attached to the bed B at p', as shown in Fig. 2, and one end of the wire r is attached to the rotary head C at r'. As the helix R on the rotary head is arranged to rotate with the same, a circular conducting-ring or collector R' is provided to serve as a means of connection with the other end of said helix. This conducting-ring R' is shown conveniently situated upon the shell or casing r', it being understood, however, that it is insulated therefrom. A suitable spring contact-piece S is then secured upon the cover X, which incloses the crusher and is arranged to make contact with the ring R'. By such arrangement when an energizing-current traverses the helices P and R the bed B and rotary head C will become electromagnets. Their opposing faces will therefore become pole-pieces and will attract each other with considerable force. This force is of course dependent upon the strength of the energizing-current and the distance between the opposing magnetic faces and may be regulated in accordance with well-known laws. It will be observed that not only may great crushing force and great efficiency of action be obtained by such arrangement, but the construction of the rotary head may be very light and simple and the necessity of employing cumbersome mechanisms for exerting a crushing pressure is completely eliminated.

What I claim as my invention is—

1. A crusher comprising a bed having an upper face which provides a lower series of concentrically-disposed annular ball races or tracks; a number of sets of balls or the like, whereof each set works in one of the races or tracks thus provided; and a rotary head supported above the bed and constructed with a lower face which provides an upper series

of concentrically-disposed annular ball races or tracks which lie respectively opposite to the races or tracks provided by the bed, 70 and upon the sets of balls working therein, and which are capable of independent shift or adjustment relatively to the rotary head, and in a direction parallel with the axis of rotation and toward and away from the races 75 or tracks provided by the bed: whereby each upper ball race or track can automatically adjust itself with reference to the set of balls upon which it rests, and independently of the other upper races or tracks, as set forth. 80

2. A crusher comprising a bed having an upper face which provides a lower series of concentrically-disposed annular ball races or tracks; a number of sets of balls or the like, whereof each set works in one of the races or 85 tracks thus provided; a rotary head supported in position above the bed; a series of concentrically-disposed annular rotary bearings providing an upper series of concentric annular ball races or tracks which lie respectively opposite to the races or tracks provided by the bed, and upon the sets of balls confined therein, and having with the rotary head sliding connections adapted to permit their rise and fall relatively to the rotary 95 head and independently of one another, and a helix for magnetizing the said rotary head, whereby the latter will tend to attract the said bed.

3. A crusher comprising a bed having an 100 upper conical face provided with a series of concentric annular grooves which form ball races or tracks; a number of sets of balls or the like, whereof each set works in one of the races or tracks thus formed; a rotary 105 head supported above the bed-face and arranged for vertical shift or self-adjustment relatively thereto, said rotary head being provided with a central feed-opening which leads to the central portion of the bed-face, and also with an annular groove arranged above the innermost groove thereof; and a series of concentrically-disposed annular bearings having their lower faces grooved so as to provide an upper series of concentric annular ball 115 races or tracks which lie respectively opposite to the races or tracks provided by the bed, and upon the sets of balls working therein, and also having with the rotary head sliding connections adapted to permit their rise 120 and fall relatively to the rotary head and independently of one another.

4. A crusher comprising one or more sets of iron crushing-balls or the like which are therefore susceptible to magnetic influence; a couple of relatively rotatory crushing members providing one or more pairs of oppositely-arranged races or tracks between which the set or sets of balls can work, one of said members being constructed of iron and therefore 125 magnetically susceptible; a magnet attracting both the iron balls and the races or tracks of the magnetically - susceptible crushing member toward the races of the other mem-

- ber, and a helix for energizing the said magnet, as set forth.
5. A crusher comprising one or more sets of crushing-balls or the like; a couple of relatively rotatory crushing members providing one or more pairs of oppositely-arranged races or tracks between which the set or sets of balls can work; a couple of coattracting magnetic pole-pieces lying on opposite sides of the balls, and tending to draw the oppositely arranged races or tracks of the two members toward one another, and means for magnetizing the said pole-pieces, as set forth.
10. A crusher comprising one or more sets of magnetically-susceptible crushing-balls or the like; a couple of relatively rotatory magnetically-susceptible crushing members providing one or more pairs of oppositely-arranged races or tracks between which the set or sets of balls can work; and wire helices arranged upon said members, and adapted, when energized, to form of the opposing races or tracks thereof, coattracting magnetic pole-pieces capable of attracting one another and the balls, as set forth.
15. A crusher comprising a bed providing a series of concentric annular ball races or tracks; a number of sets of balls working in the races or tracks thus provided; a rotary head arranged above the bed and providing a corresponding series of concentric annular ball races or tracks, and having an upwardly-extending tubular central portion providing a feed-opening and a core or spindle; and a wire helix wound about the core or spindle thus provided and adapted, when energized, to magnetize the ball races or tracks provided by the rotary head, as set forth.
20. A crusher comprising a bed having an upper face provided with a series of concentric annular grooves providing lower ball races or tracks, and also provided with a series of amalgamating-plates arranged between the grooves; a number of sets of balls working in the races or tracks thus provided; and a rotary head providing an upper corresponding series of concentric annular ball races or tracks, and having a series of covered openings adapted to permit the removal and re-placement of the amalgamating-plates without necessitating a removal of the rotary head, as set forth.
25. A crusher comprising a bed providing one or more annular ball races or tracks; one or more sets of balls working in the race or races thus provided; a rotary head arranged above the bed; and one or more bearings providing a corresponding number of annular ball races or tracks and respectively comprising a series of sections which are connected with the rotary head so as to be capable of independent shift or adjustment relatively thereto, and in a direction parallel with the axis of rotation and toward and away from the races or tracks provided by the bed, as set forth.
30. A crusher comprising a bed providing a series of concentric annular ball races or tracks; a number of sets of balls working in the races or tracks thus provided; a rotary head arranged above the bed; a series of concentric annular bearings providing a corresponding series of annular ball races or tracks, and respectively comprising a series of independently-adjustable arc-shaped sections suspended from the rotary head and connected with the same so as to permit of their adjusting themselves independently of one another; and spring means for forcing such sections independently downward upon the balls, substantially as described.
35. A crusher comprising one or more sets of crushing-balls or the like; a couple of relatively rotatory iron crushing members providing one or more pairs of oppositely-arranged races or tracks between which the set or sets of balls can work; a helix arranged upon one of said crushing members, and means for energizing the said helix, whereby the crushing member thus magnetized will tend to attract both the balls and the other crushing member.
40. A crusher comprising a bed having a plurality of concentrically-arranged annular ball races or tracks; a rotary head arranged above the said bed and provided with a corresponding series of ball races or tracks, and a number of crushing-balls or the like arranged to work between the said oppositely-arranged tracks or races; the said rotary head being arranged for a slight vertical self-adjustment, and the ball races or tracks of the rotary head having, with the exception of the innermost track, a sliding connection with the said rotary head adapted to permit an independent self-adjustment on the part of said tracks or races; the said innermost track or race being rigid with the rotary head.
45. A crusher comprising a bed having a plurality of concentrically-arranged annular ball races or tracks; a rotary head arranged above the said bed and provided with a corresponding series of ball races or tracks, and a number of crushing-balls or the like arranged to work between the said oppositely-arranged tracks or races; means for magnetizing the said bed, and means for magnetizing the said rotary head; the said rotary head being arranged for a slight vertical self-adjustment, and the ball races or tracks of the rotary head having, with the exception of the innermost track, a sliding connection with the said rotary head adapted to permit an independent self-adjustment on the part of said tracks or races; the said innermost track or race being rigid with the rotary head.
50. A crusher comprising a bed having a plurality of concentrically-arranged annular ball races or tracks and a downwardly-extending central tubular portion; a rotary head having an upwardly-extending central tubular portion, said head being arranged above the said bed and provided with a corresponding series of ball races or tracks; a number of crushing-balls arranged to work between the

said oppositely-arranged tracks or races; wire helices arranged upon the said tubular portions of the bed and rotary head; a shaft arranged to extend upwardly through the center 5 of the bed and engaging the rotary head for the purpose of rotating the latter; means for driving the said shaft, and means for energiz-

ing the said helices for the purpose of forming coattracting pole-pieces of the said bed and rotary head.
